Des. 221,043
Patented June 29, 1971

221,043

MESSAGE DISPLAY UNIT

Kenneth Taishoff, 117 N. Park St.,

Cadillac, Mich. 49601

Filed Dec. 17, 1969, Ser. No. 20,549

Term of patent 14 years

Int. Cl. D20—03

U.S. Cl. D96—12

FIG. 1.

FIG. 3.

FIG. 2.

FIG. 4.

FIG. 5.

FIG. 6.

FIG. 1 is a front perspective view of a message display unit embodying my new design;

FIG. 2 is a front elevational view thereof;

FIG. 3 is an end elevational view thereof;

FIG. 4 is a top plan view thereof;

FIG. 5 is a rear elevational view thereof; and

FIG. 6 is a cross sectional view thereof.

I claim:

The ornamental design for a message display unit, substantially as shown.
